PATENTED OCT. 16, 1906.

J. S. SMITH.

GAS PRODUCING APPARATUS.

APPLICATION FILED JULY 18, 1904.

UNITED STATES PATENT OFFICE.

JACOB S. SMITH, OF CHICAGO, ILLINOIS.

GAS-PRODUCING APPARATUS.

No. 833,256.

Specification of Letters Patent.

Patented Oct. 16, 1908.

Application filed July 18, 1904. Serial No. 218,929.

To all whom it may concern:

Be it known that I, JACOB S. SMITH, of the city of Chicago, in the county of Cook and State of Illinois, have invented certain new and useful Improvements in Gas-Producing Apparatus, of which the following is a specification.

This invention relates to improvements in gas-producing apparatus, comprising a gas generator or retort, a plurality of carbureters, a condensing-scrubber, and a pump for exhausting the gas from the generator through the carbureters and scrubber and forcing it into a gasometer or other receptacle and may be directly into the main and in which gas is produced from hydrocarbons in conjunction with steam and air, or either.

My invention further relates to a gas-producing apparatus in which a closed retort is heated externally, but more particularly to that in which the retort derives its heat from the internal combustion of the gas-producing materials employed therein.

In the manufacture of gas from hydrocarbons there is always present dissociated hydrogen, the volume of which is substantially increased when steam is used in conjunction therewith, which dissociated hydrogen, owing to its specific gravity, is the first to escape from the generator or the cupolas and flows into the scrubber and is thence discharged into the main, while in the meantime the mixed gases pass more slowly without taking up or combining a full portion of this dissociated hydrogen, with the result that the heat units of a gas produced from a given amount of hydrocarbons and steam injected into a generator-retort are reduced in numbers and degree corresponding with that otherwise producible by the combining of this dissociated hydrogen with the hydrocarbon vapors previous to their discharge into the scrubber, the gasometer, main, or other receptacle, and as their volume is quite large the desirability of their fixed combination is proportionately desirable and important.

The prime object of my invention is to gasify hydrocarbons and to provide means so controlling the dissociated hydrogen of steam liberated during the generation of gas in the generator or retort that the fixed combination of substantially all of the dissociated hydrogen and other elements with the carbon-vapors is insured, and the heat units of the gas produced is correspondingly increased.

Another object is to provide means producing a continuous return circulation of gas through a plurality of carbureters and concurrently therewith a discharge of a portion of the gaseous contents of the carbureters to the scrubber or other receptacle.

A further object is to provide means where by hydrocarbons supplied at any point into or between a plurality of carbureters, or either of them, are subjected to and mixed with gaseous products at the point of their discharge from the generator, and thereby correspondingly raised in temperature before they are discharged from the carbureter.

A still further object is a gas generator or retort so constructed in itself and provided with hydrocarbon, steam, and air injector so arranged as to substantially promote the breaking up of its composition, mixing and combining atoms and their exposure to heat, and therefore the volume of fixed gas evolved from any given quantity of said materials and each of them when supplied to the generator in whole or in part.

With these ends in view my invention consists in certain features of novelty in the construction and combination of parts by which the said objects and certain other objects hereinafter appearing are attained, all as fully described with reference to the accompanying drawings and more particularly pointed out in the claims.

In the accompanying drawings, Figure 1 represents a gas-producing apparatus embodying my invention, with a gas-generator, carbureters, scrubber, the overflow for the latter, and a coal-tar, receptacle shown in vertical and longitudinal section and an exhaust-pump and its connection with the scrubber in side elevation. Fig. 2 is an enlarged end view of the injector for hydrocarbon, steam, and air to the generator. Fig. 3 is an enlarged vertical section, in part, of the combustion-chamber, of the generator-retort, and a portion of the same above the combustion-chamber.

Similar letters and numerals of reference indicate the same parts in the several figures of the drawings.

A represents a brick-lined generator, retort, or cupola, within which and independent of the brick lining is built a cone-shaped combustion-chamber having an inner or "breaker" wall 1, and so termed because the injected hydrocarbons or other liquid em-

ployed are injected against said wall with such force and violence as to substantially break up and thereby promote the atomizing of said liquid, to which end there is an 5 opening 3 in the wall of the generator-retort opposite said breaker-wall, a pipe 6, inclosing a steam-supply pipe 7, but larger in diameter, forming an annular chamber through which the hydrocarbons may be supplied and 10 carried forward by the steam-pipe 7 against the breaker-wall, the said pipes 6 and 7 being so arranged that they may be readily changed to adapt them for thicker or thinner fluids, as desired.

15 The hydrocarbon-pipe 6 is surrounded by a number of small steam-pipes 8, and all of said pipe ends and their discharge-openings point so as to discharge directly against the breaker-wall in a line preferably at a right 20 angle thereto, the steam-pipe 7 being provided with an ordinary valve 7^a, as is also hydrocarbon-pipe 6 at some point therein, though not so shown, for the purpose of regulating the supply of hydrocarbon to the retort.

25 Within the retort and with its plane just above that occupied by the injector just described is what for convenience is termed a "combustion-cone" 12, provided with an 30 opening 2, the apex of the cone terminating about one-fourth the length of the retort above its bottom. Supported by this cone is a checker-work 4, which projects upwardly in the generator-retort in a plane at or just 35 above the discharge-orifice 5 thereof. The length in diameter of the checker-work 4 is such that there is formed between it and the side and top walls of the retort a vaporizing-chamber 4^a for hydrocarbons injected through 40 the pipes 9 respectively at the side and top of the generator and as may be at as many different points as seem desirable, and pipes 23 and 24 are inserted within pipe 9 for the introduction also of steam or air, or both, as desired.

50 The discharge orifice or pipe 5 opens into the side of a carbureter B at or near the lower end thereof, which carbureter is filled from its bottom practically to the top with a checker-work 5^a, into which hydrocarbons may be discharged through a number of pipes 9 at intervals of its side and also in the top thereof. Next the carbureter B is another carbureter C, which two carbureters 55 are connected by a pipe or passage 11 at their sides and at or near their upper ends, the carbureter C being filled with checker-work 5^a in substantially if not the identical manner of carbureter B, and carbureter C, 60 like carbureter B, may be supplied with hydrocarbons through the pipe 9, projecting through its upper end, and may also have further pipes for the same purpose opening into the sides thereof, as shown for the carbureter B.

65 Carbureter C is connected with a scrubber D by a pipe or passage 13, which is located at the sides and at or near the lower ends of said carbureters and scrubber, the scrubber D, as usual, being provided with plates 14 70 throughout its length arranged to form a zigzag passage for the ascending gases and for the descending of cold water supplied to the pipe 15 at the upper end thereof, as is usual in scrubbers, the lower end of the 75 scrubber being provided with a pipe 16, discharging into a receptacle 17 at a point near its bottom, which receptacle has a discharge or overflow pipe 18 at a point above the discharge end of pipe 16 and at or toward the 80 upper end of the receptacle for the discharge of water and coal-tar flowing from the scrubber down through the pipe 16.

85 The gas in the scrubber is discharged therefrom through a pipe 19, opening into the scrubber at or near its top, connected with an exhaust-pump F, from which the gas is forced onwardly through a pipe 20 to the main, gasometer, or other receptacle, the exhaust-pump also serving to exhaust gas from 90 the generator as fast as generated, thence upwardly through the length of the carbureter B and downwardly through the carbureter C into the lower portion of the carbureter, whence it discharges into the scrubber and 95 from the upper end thereof, as before described.

From the construction so far described it will be seen that the gases from the generator after passing upwardly the full length of the 100 carbureter B are thence forced to descend through the entire length of the carbureter C before discharging into the scrubber and that the dissociated hydrogen tending to accumulate in the upper portions of the carbureters B and C may be made to combine with the carbon-vapors resulting from the volatilizing of hydrocarbons supplied through the pipe 9 in the carbureters or entering from the generator A. In order, however, to insure as 105 far as possible a perfect combination with the carbon-vapors of all dissociated hydrogen, the best results are secured by not only re-conducting a portion of the gases from the carbureter C back to the carbureter B by 115 means not interfering with the continuous discharge of a portion of the gases in the carbureter C to the scrubber, but at such a point in the carbureter B as will compel the returned gases to traverse the length of the 120 carbureter and directly across the path of the gases discharging from the generator, at which point there exists the highest degree of heat possible in the carbureter B. To these 125 ends the bottom ends of the carbureters are coupled together by a return-pipe E, the diametrical bore of which is somewhat less than the bore of the discharge-passages 5, 11, and 13, which return-pipe E is provided with a fan G, cooled by a circulation of water there- 130

through introduced through a pipe 21. This return may also be provided with one or more pipes 9 for supplying hydrocarbon at one or more points therein, preferably at the 5 points indicated in the drawings, or steam may be substituted for the fan G to create current by means of the injector H.

The operation of the apparatus is as follows: Liquid hydrocarbons or other gas-making materials are introduced into the generator through the pipe 6 and ignited. The pump F is then started, and when the combustion-cone 12 has become sufficiently heated steam is turned on through the central pipe 7 with sufficient force to violently atomize the liquids against the breaker-wall 1 of the cone 12, and at the same time steam is admitted through the surrounding pipes 8, which forms a sheet of steam around the combustion, with the air passing in between the surrounding and central pipes, which may be either by the induced draft or forced by other means. The products of this combustion are brought together in the cone 12 and pass out through its top into the checker-work above, into and through the cupolas B, C, and scrubber D, and through the pump. When the cupolas B and C have become heated, as desired, the fan G is set in motion and a 25 part of the gas is taken from cupola C and passed into cupola B, causing a continuous circulation between and in the two cupolas, which current meets and mixes with the heated products arising from the generator. The 30 gas leaving cupola C enters the condenser and scrubber at the bottom, into which water is introduced at the top, which falls through the perforated pans in the form of spray. The hot gas as it enters the cupola 35 converts the spray into steam, which mixes and mingles with the gas, condensing as it rises by meeting the cooler water falling from above, cleanses the gas of excessive carbon or unassociated tar, which passes down and out with the falling water through the pipes 40 at the bottom of D into the trap G below, the operation being fully controlled without interruption by the continuous introduction of the gas-making materials in the generator 45 50 A and the action of the pump F and the fan G, resulting in the continuous manufacture with the resubmission of gas to the action and effect of the heats of generation and the carbureting-cupolas. Additional carbureting materials may be added or introduced in the circulation at any point between the combustion-chamber in the generator and scrubber D, preferably immediate above the entrance of the generator-gas to 55 60 65 cupola B, and also at a point between the cupolas in the connecting-pipes. When oil or other gas-making materials in suitable form, together with steam and air, are introduced in the bottom of A and ignited, the products of this combustion pass upward into B, which

is filled with brick checker-work, the gases so generated ascend through this cupola and pass into C, also filled with brick checker-work, at the top moving downward to the opening into the scrubber D, thence upward 70 and through the pipes provided, controlled in its circulation by a pump F, attached thereto. During this circulation the fan G is started, which takes a part of the gas from C at the bottom and forces it into B at the bottom, thus forming a circulation around and through B and C. It is plain that if the pump F, attached to the lead-away pipes, be stopped, a continuous circuit of the entire current would be maintained so long as the 75 fan G continued in motion; but to assure a circulation from the generator a part of the gas must be removed by the pump F. Therefore it would be impossible to pass all of the gas made in the generator through the fan, 80 and it is not so intended, only so much of it as will bring the standard of the whole up to the required excellence. The refractory hydrocarbons by this circulation are again subjected to the heats arising from the generator 85 to dissociate them and are again passed through the carbureters to take up freshly-liberated hydrogen in the gas coming from the generator, and so on continuing the operation until the absorption or dissolution of 90 the refractory elements are satisfactorily completed, which is ascertained by the quality of the gas coming from the pump, which may be run fast or slow to govern the output, and the fan may be run slow or fast to maintain 95 the desired current inside the cupolas. It is well known that hydrogen gas is much lighter than any other of the gases generated in this manner, that its tendency is to rapidly rise as fast as liberated, seeking the 100 highest point or top of the cupola or cupolas, and although checker-work is introduced in cupolas to arrest and mix it with vaporizing-carbon much of it escapes contact and remains as free hydrogen. To obviate this I 105 have introduced the second vertical carbureting-cupola C, which admits the generated gases at the top and discharges the same at the bottom. It is obvious that the unassociated hydrogen must mix with the generated 110 vapors in passing downward, as it cannot move faster than the heavier gases and in passage through the checker-work of this cupola it is intimately mingled or mixed with the vaporized carbon, the purpose of this second carbureter or cupola C being to force the vapors or generated gases under gasifying heat to move as nearly as possible together in passing through the brick checker-work with 115 which the cupola is filled. It may be that the passage of the gases from the generator through carbureters B and C will often form a desired combination or result in a desired quality, in which case the gas may be taken off at the bottom of C and the motion of the 120 125 130

- fan G may be suspended; but to more completely volatilize and combine the heavy hydrocarbons and diminish the tar products the greater portion of the gases should be passed, 5 by means of the fan G, from C to B and again be subjected to the heats from the generator and the action of the carbureters B and C, and such circulation should be maintained and such portions of the whole passed through 10 B and C as will produce the desired result in the gas drawn off by the pump F, the object being to again submit or resubmit repeatedly the refractory particles or elements in the gas as made in the generator to the 15 heats of generation and combine them with the unassociated hydrogen, dioxid, or other elements seeking combination.
- While I have shown and described the employment of but two carbureters, it would be 20 no departure from the spirit of my invention to employ an additional number, either in the same or a different relation from the two carbureters, as shown, not to omit therefrom the carbon-supply pipes 9 and to fill the 25 same or partly fill the same with refractory material of a different nature and in a different arrangement, nor to connect the two carbureters by straight pipe connection between their sides at or near the bottom ends 30 of said carbureters instead of as shown, or to employ any other well-known form of scrubbers or substitute for the exhaust-pump. It is also obvious that any other well-known form or arrangement of retort than that 35 shown may be used without a departure from the spirit of my invention; and so, also, as to the form and arrangement of the parts constituting the injector for the hydrocarbons, steam and air, or either of them.
- 40 Having thus described my invention, what I claim as new therein, and desire to secure by Letters Patent, is—
1. In a gas-producing apparatus the combination with a gas-generator of a plurality of carbureters and means connecting said generator and carbureters, whereby the gas-discharge from the generator ascends through one of said carbureters and descends through the other carbureter, and a portion of said 45 gas is returned to the first carbureter before its discharge to a scrubber or other receptacle, substantially as described.
  2. In a gas-producing apparatus, the combination with a gas-generator, a scrubber, a 50 plurality of carbureters between and connecting with said generator and scrubber and with each other, of means whereby gases discharged from the generator are caused to alternately and respectively ascend and descend through said carbureters and a portion of said gases are returned to the first carbureter before discharging into the scrubber at 55

or near the bottom thereof, substantially as described.

3. In a gas-producing apparatus, the combination with a generator of a plurality of carbureters, means for discharging the gas from the upper end of the generator into the lower end of one of said carbureters, means connecting the upper ends of said carbureters, 65 means for discharging the gas from the lower end of the second carbureter, means for inducing a continuous circulation of gas from the generator through a plurality of carbureters, means connecting the lower ends of both carbureters with each other and means inducing a return of gas from one carbureter to another simultaneously with a discharge of a portion of the gas entirely from said carbureters onward to its final destination, substantially as 70 described.

4. In a gas-producing apparatus a plurality of carbureters in combination with means connecting said carbureters and means for producing a continuous circulation of gas 85 through said carbureters and simultaneously therewith a return of a portion of said gas from one of said carbureters to the other, substantially as described.

5. In a gas-producing apparatus, a generator, a plurality of carbureters and a scrubber and means whereby gases are discharged from the upper part of the generator at or near the bottom of the carbureter next thereto, and from the upper part of said carbureter into the upper part of the adjacent carbureter and therefrom near the bottom thereof into the scrubber at or near its lower end in combination with a pipe connecting said carbureters at a point below the supply 90 and discharge connections thereof, and a blower arranged in said pipe or passage whereby a portion of the gases in the second carbureter are returned to the first carbureter in the path of the gases discharging from 95 the generator, substantially as described.

6. In a gas-producing apparatus a plurality of carbureters connected at or near their upper ends in combination with a generator structure discharging from its upper 100 end into and at or near the bottom of the adjacent carbureter, said generator being provided with a cone forming the top of its combustion-chamber, and with a checker-work supported by said cone and surrounded by 105 a supplemental combustion-chamber and means for supplying hydrocarbons to both of said combustion-chambers and also air and steam to either combustion-chamber, substantially as described.
